UNITED STATES PATENT OFFICE.

HENRY AUGUST PREUSS, OF HAMBURG, GERMANY, ASSIGNOR OF FORTY ONE-HUNDREDTHIS TO FRANCISCO VILMAR, OF RIO DE JANEIRO, BRAZIL.

MEANS FOR OPERATIVELY CONNECTING A GRAMOPHONE WITH AN AUTOMATIC MUSICAL INSTRUMENT.

1,145,792.

Specification of Letters Patent.

Patented July 6, 1915.

Application filed January 28, 1914. Serial No. 815,055.

To all whom it may concern:

Be it known that I, HENRY AUGUST PREUSS, a citizen and resident of Hamburg, Germany, have invented a new Means for Operatively Connecting a Gramophone with an Automatic Musical Instrument, of which the following is a specification.

In playing gramophones accompanied by an automatic musical instrument there is the difficulty of producing a simultaneous performance of the two instruments in perfect synchronism and harmony. This difficulty mainly results from the variability of the music sheet used for operating the musical instruments. Such a sheet naturally is subject to the influences of weather by which the sheet constantly is lengthened or shortened and therefore changes the distances of the tones following one another. Such variations in the succession of the sounds is very soon perceptible and gradually increases to such an extent, that it appears impossible to allow the instruments to play together. Heretofore the music sheet was driven in this manner, that the sheet drum was set to rotate by the train of gearings of the gramophone, or the gramophone was allowed to be driven directly from the motor of the piano.

According to the present invention the music sheet is driven independently from the sheet drum. This object in view, the music sheet is provided with a special row of perforations on each side into which the teeth of a star wheel in rotating feeds the music sheets at a constant speed. In making use of this device the variations in the length of the music sheet arising from the varying temperature and the moisture of the air have no effect on the synchronism, since the variation of the short spaces between the consecutive openings are too short to allow of an incorrect engagement of the following teeth of the star wheel.

In Figure 1 of the drawing part of an automatic piano is shown in combination with a gramophone in a sectional side view. Fig. 2 is the plan of this device, Fig. 3 the front view of its lower part, and Fig. 4 is a perspective view of a portion of the gearing.

In the construction shown it is assumed, that the music sheet *a*, which is wound from either of the rolls *p* and *p'*, is driven by the

train of gearings *b* of the gramophone *c*, provided with the usual vertical shaft 2. 55 The shaft 2 may be driven through any of the gearing commonly employed for this purpose, and for the purposes of illustration I have shown the same provided with a pinion 3 in mesh with a gear wheel 4 mounted on a shaft 6 arranged parallel with the shaft 2, said shaft 6 being further provided with a pinion 5 meshing with a gear wheel *b* driven by any suitable type of motor, as indicated in Fig. 1. The motor gear wheel *b* also meshes with a pinion 7 mounted on a shaft 8 carrying a gear wheel *d*. The wheel *d* of the said gearings *b* meshes with a wheel *e* which is journaled in a movable arm *f* fixed to the shaft *h* which is journaled in a 70 bracket *f'*. The wheel *e* meshes with another wheel *g* rotatably mounted on the shaft *h*. A spring *f''* tends to move the arm *f* in such direction as to secure the engagement of the gear wheels *e* and *d*. The shaft 75 *h* is provided with a bevel wheel *i* at its lower end engaging another bevel wheel *k*, the shaft *k'* of which carries a spur wheel *e* on the shaft *m*. The shaft *m* is journaled 80 preferably in close proximity to the tracker board *a'* with which the movable music sheet *a* contacts in the usual manner. On this shaft a star wheel or drum *n* is firmly attached. The sheet drum *p* is driven from 85 the driving shaft *q* by the gears *r* and *r'*. The gear wheel *r'* is not fixedly mounted on the shaft *p* but is loosely mounted thereon in such a manner as to normally drive the shaft through friction of its hub thereon. Such an arrangement permits the record *a* to be driven independently by the drive drum *n* without interference from the roll *p* and its actuating mechanism, the latter providing a slip drive to wind up the 90 record as fed by the drive drum. By these means the music sheet fed by the star drum *n* is wound up by the drum *p* but is not pulled along by the latter by force.

Provision is made to allow the piano to be 100 played independently from the gramophone. For this purpose the star wheel or drum *n* is removed and by means of a pin *s* the gear *r'* carrying suitable perforations is coupled to the sheet roll or drum *p*. When however 105 it is desired to allow the piano to play to-

gether with the gramophone the coupling pin *s* which is preferably a screw pin is withdrawn.

As has been said above the shaft of the wheel *e* is not journaled in a fixed point but in an arm *f* which is rotatable about the shaft *h*. This will enable the operator to disengage the wheel *e* from the wheel *d*, which is preferably done by the aid of the slide *t* provided with a handle *t'*. The slide *t* carries below an oblique shoulder *t*² in the path of a pin *f'* on the arm *f*. When the slide *t* is moved inwardly the pin *f'* will be shifted sideward by the oblique surface 15 of the shoulder *t*², thus disengaging the wheel *e* from the wheel *d*. The slide may also be used to stop the gramophone. To this end the slide *t* will engage a roller *u* by two upper projections *t*³. The roller *u* 20 is arranged on a rotatable arm *v*, having beyond its axis of rotation a pawl *w* adapted to engage the rim of a disk *x* connected with the gramophone. Thus when the slide *t* is moved inwardly to stop the driving 25 mechanism of the music sheet, the gramophone will also be stopped by the pawl *w*.

It will be evident, that the driving mechanism for the musical instrument consisting of the star wheel or star drum and the rows 30 of perforation in the music sheet can be made use of in recording as well as in reproducing.

I claim:

1. The combination with a phonograph, 35 and operating mechanism therefor, of an automatic musical instrument having a take-up roll, a record for said automatic musical instrument, and means directly connected to and positively driving said automatic instrument record independent of the take-up roll, substantially as described.

2. The combination with a phonograph, 45 and operating mechanism therefor, of an automatic musical instrument, a record therefor, a roll for initially holding said record, a take-up roll for receiving the record as played, means directly connected to and positively driving said automatic instrument record independent of the take-up 50 roll, connections for actuating said means from the phonograph operating mechanism, and means for actuating said take-up roll to wind up the automatic instrument record as driven from said first-named means, substantially as described.

3. In a device for synchronizing automatic musical instruments, the combination 60 of an automatic musical instrument, a record therefor, a roll for initially holding said record, a roll for receiving the record as played, a slip drive mechanism for said receiving roll, means for positively connecting together the members of said slip drive mechanism to provide a positive drive mechanism, removable drive means independent

of said receiving roll in operative connection with the record for actuating the same, a phonograph, and connections between said phonograph and removable drive means for operating the automatic instrument record 70 synchronously with the phonograph, substantially as described.

4. In a device for synchronizing automatic musical instruments, the combination 75 of an automatic musical instrument, a record therefor, a roll for initially holding said record, a roll for receiving the record as played, a transmission element frictionally connected with said receiving roll, means for driving said transmission element to normally wind up said record, means for connecting said transmission element positively to said receiving roll, drive means independent of said receiving roll in operative connection with the record for actuating 80 the same, a phonograph, and connections between said phonograph and drive means for operating the automatic instrument record synchronously with the phonograph, substantially as described.

5. In a device for synchronizing automatic musical instruments, the combination 85 of an automatic musical instrument, a record therefor, a roll for initially holding said record, a roll for receiving the record as 90 played, a shaft for said receiving roll, a gear wheel frictionally mounted thereon, means for driving said receiving roll through said gear wheel, a pin for positively connecting said gear wheel to said receiving roll, drive 95 means independent of said receiving roll in operative connection with the record for actuating the same, a phonograph, and connections between said phonograph and drive means for operating the automatic instrument record synchronously with the phonograph, substantially as described.

6. In a device for synchronizing automatic musical instruments, the combination 100 of an automatic musical instrument, a record therefor, drive means in operative connection with the record for actuating the same, a phonograph, connections between said phonograph and drive means for operating the automatic instrument record synchronously from the phonograph, a pivoted 105 arm for carrying one element of said connections, and means for swinging said pivoted arm to disengage the associated element from said connections, substantially as 110 described.

7. In a device for synchronizing automatic musical instruments, the combination 115 of an automatic musical instrument, a record therefor, a phonograph, operating mechanism therefor, connections between said operating mechanism and the automatic instrument record for driving the same synchronously with the phonograph, a pivoted 120 arm carrying one element of said connec- 125

tions, a cam block for moving said arm to disengage the associated element from said connections, and means for actuating said cam block, substantially as described.

- 5 8. In a device for synchronizing automatic musical instruments, the combination of an automatic musical instrument, a record therefor, a roll for initially holding said record, a roll for receiving the record
- 10 as played, drive means independent of said rolls in operative connection with the record for actuating the same, a phonograph, connections between said phonograph and drive means for actuating the automatic instrument
- 15 record synchronously from the phonograph, and means for disengaging said connections including a pivoted arm, one element of said connections mounted on the free end of said arm and adapted to be moved to disengage said connections, a lug carried by said arm, a cam block engaging said lug to move the arm to disengage said element, and an operating rod for moving the said cam block, substantially as described.
- 20 9. In a device for synchronizing auto-

matic musical instruments, the combination of an automatic musical instrument, a record therefor, a roll for initially holding said record, a roll for receiving the record as 30 played, drive means in operative connection with said record for actuating the same, a phonograph, connections between said phonograph and driving means for actuating the automatic instrument record synchronously from the phonograph, means for disengaging said connections including a pivoted arm, one element of said connections carried on the free end of said arm, a lug on 35 said arm, a cam block for engaging said lug to move the arm to disengage said element, an operating rod for moving said cam block, means for normally tending to maintain said connections in operative engagement, and means associated with and operated by said 40 operating rod for braking the phonograph when said connections are disconnected, substantially as described.
